(57) **CLAIM**

I claim the ornamental design for adapter for attaching a bottle to a sealing pistol, as shown and described.

DESCRIPTION

FIG. 1 shows a first perspective view of an adapter for attaching a sealing bottle to a sealing pistol;
FIG. 2 shows a second perspective view of the adapter of FIG. 1;

FIG. 3 shows a lateral view of the adapter of FIG. 1;
FIG. 4 shows a different lateral view of the adapter of FIG. 1;
FIG. 5 shows a front view of the adapter of FIG. 4; and,
FIG. 6 shows a rear view of the adapter of FIG. 4.
The portions of the adapter shown in broken lines form no part of the claimed design.
